UNITED STATES PATENT OFFICE

132,493

DESIGN FOR A DRESS ENSEMBLE

William Maidman, New York, N. Y.

Application April 21, 1942, Serial No. 106,648

Term of patent 3½ years

To all whom it may concern:

Be it known that I, William Maidman, a citizen of the United States of America, residing in New York city, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.
Fig. 3 is a front view of the dress member.
Fig. 4 is a rear view of Fig. 3.
Fig. 5 is an enlarged view of one of the pocket portions of the ensemble shown in Figure 1.

I claim:
The ornamental design for a dress ensemble, substantially as shown and described.

WILLIAM MAIDMAN.
